CLAIM

The ornamental design for automatic coffee machine, as shown and described.

DESCRIPTION

FIG. 1 is a front perspective view of an automatic coffee machine showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top, plan view thereof;

FIG. 7 is a bottom view thereof;

FIG. 8 is a front elevational view of an automatic coffee machine showing a second embodiment of my new design; and,

FIG. 9 is a top plan view thereof.

The rear, side, and bottom views of the second embodiment are identical to those of the first embodiment.
